CLAIM

The ornamental design for a display screen or portion thereof with animated graphical user interface, as shown and described.

DESCRIPTION

FIG. 1 is a front view of a first embodiment showing a first image in a sequence of a display screen or portion thereof with animated graphical user interface, showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of a second embodiment showing a first image in a sequence of a display screen or portion thereof with animated graphical user interface;

FIG. 9 is a front view of a second image thereof;

FIG. 10 is a front view of a third image thereof;

FIG. 11 is a front view of a fourth image thereof;

FIG. 12 is a front view of a fifth image thereof;

FIG. 13 is a front view of a sixth image thereof; and,

FIG. 14 is a front view of a seventh image thereof.

The appearance of the animated graphical user interface sequentially transitions between the images shown in FIGS. 1-7 and 8-14. The process or period in which one image transitions to another image forms no part of the claimed design.

The broken line showing a display screen in FIGS. 1-7, and the outer broken line showing a device, and the inner broken line showing a display screen in FIGS. 8-14 form no part of the claimed design.
